UNITED STATES PATENT OFFICE.

NATHANIAL S. PETERMAN, OF GARWIN, IOWA.

BURIAL-CASKET.

1,003,943.

Specification of Letters Patent. Patented Sept. 19, 1911.

Application filed March 15, 1910. Serial No. 549,465.

To all whom it may concern:

Be it known that I, NATHANIAL S. PETERMAN, a citizen of the United States, residing at Garwin, in the county of Tama and State 5 of Iowa, have invented a new and useful Improvement in Burial-Caskets, of which the following is a specification.

This invention relates to certain new and useful improvements in burial caskets, the 10 object being to combine in one casket four styles of caskets, whereby any one of said styles can be used.

Another object of my invention is to provide a casket which is exceedingly cheap and 15 simple in construction, and one in which the cover, the lid and the cover molding are so connected together that they will be held in their proper position, and yet be capable of being moved so as to form different style 20 caskets.

A still further object of my invention is to provide the cover with a steel frame to which are hinged the sections of the cover molding, whereby said molding and the lid 25 sections carried thereby will be supported firmly when the cover is thrown into an opened position.

A still further object of my invention is to provide novel means for holding the respective hinged sections of the casket in a 30 closed position, so that all danger of the same becoming unfastened accidentally, when in use is prevented.

With these and other objects in view, the 35 invention consists in the novel features of combination, construction and arrangement of parts, hereinafter fully described and pointed out in the claim.

In the drawing forming a part of this 40 specification:—Figure 1 is a top plan view of my improved burial casket showing the molding sections swung outwardly. Fig. 2 is a side elevation showing the cover raised, the side dropped and one section of the lid 45 and molding swung outwardly.

In carrying out my improved invention, I employ a body A, which may be of any style and design desired, and is provided with a hinged side section B, which can be 50 dropped as shown in Fig. 2 and is held in a closed position by fastening members clearly shown, so as to prevent the sides from

dropping down accidentally, and said side is also locked by the cover as will be hereinafter described.

55

Pivottally mounted on the body A is a cover C which comprises a fixed section D and a movable section E, the movable section E being carried by a rectangular metal frame F which is connected to the fixed section C by screws as clearly shown, and said fixed section carries a catch C', coacting with a keeper C² mounted on the upper edge of the hinged side B.

60

Secured on the frame F are hinges G 65 carrying molding sections I, the end sections carrying hooks I' adapted to coact with eyes I² carried by the side section, so as to fasten the molding sections together firmly, and the lid C³ of the fixed cover is rabbeted as shown 70 at G⁴, for the purpose hereinafter fully described.

65

Hinged to the two side sections are movable sections J and K having beveled coacting edges so as to hold the meeting edges 75 and to form a tight joint, and the inner edges of these lid sections rest on the reduced portion formed by the rabbet G⁴, and the outer edges rest on the end molding section which is provided with a keeper L' 80 adapted to receive a fastening member L carried by the lid section K so as to completely lock the lid sections in a closed position.

75

From the foregoing description it will be 85 seen that I have provided a burial casket which combines four styles in one, as by opening the lid sections the shrine style is formed, then by dropping the molding section, the half-couch style is formed, and by 90 closing the molding sections and the lid sections and by opening the cover, the full couch style is formed which allows the hinged side to be dropped.

90

Having thus fully described my invention, 95 what I claim as new and desire to secure by Letters Patent is:—

As a new article of manufacture, a burial 100 casket comprising a body having a hinged side section, a cover hinged to said body, said cover being formed of a movable section and a fixed section, a rectangular metal frame secured to the fixed section, the lid of the fixed section being provided with a reduced

portion, molding sections hinged to said frame carrying means for locking said sections together, lid sections hinged to said molding sections having beveled coacting edges, the inner ends of said sections fitting in the reduced portions of the fixed cover, and means carried by one of said lids for

locking said lids in a closed position together with means carried by the cover for locking said cover to the hinged side sections. 10

NATHANIAL S. PETERMAN.
